HYDRAULIC HOLD-DOWN FOR SQUARING SHEARS

Robert Leslie Brownlee, Chicago, Ill., assignor to
Dreis & Krump Mfg. Company, Chicago, Ill.

Application August 2, 1935, Serial No. 34,479

7 Claims. (Cl. 164—51)

This invention relates to squaring shears and the like, and more particularly to hydraulic hold-down devices therefor, and my main object is to provide a hold-down apparatus in which a set of 5 self-contained units is employed, each unit having an independent hold-down mechanism.

A further object of the invention is to arrange the hold-down units in a simple series and not dependent on any master or basic hydraulic 10 element for power.

Another object of the invention is to design the hold-down units with means for self maintenance in a highly efficient condition at all times.

15 An additional object of the invention is to provide means whereby a defect in or injury to any of the hold-down units does not disable the balance of the units or the machine for the purpose of holding down the material. An important object of the invention is to so design the hold-down 20 units that they will have an advantageous leverage for the purpose of their function.

With the above objects in view, and any others which may suggest themselves from the description to follow, a better understanding of the invention may be had by reference to the drawings, 25 in which—

Figure 1 is a front view of a portion of a squaring shear, showing the position of the novel hold-down apparatus;

Figure 2 is a section on the line 2—2 of Fig. 1; Figure 3 is a cross section on an enlarged scale of one of the hold-down units at the inception of its operation;

35 Figure 4 is a view similar to Fig. 3, showing the unit at the termination of its operation; and

Figures 5, 6 and 7 are, respectively, sections on the lines 5—5, 6—6 and 7—7 of Figure 3.

In the development of hydraulic hold-down 40 means for squaring shears, it is customary to employ a master cylinder for the fluid and to pipe the latter to a set of smaller cylinders in the hold-down zone for the control of plungers above the work to be held down. With an arrangement of 45 this kind it is necessary to employ valves and other accessory means in order to properly control the action, and should any mishap occur in one of the smaller cylinders, or something go wrong with one of the plungers, the entire mechanism must be laid up for repairs and the shear 50 kept out of operation for some time. I have therefore departed from the customary hydraulic design for the particular purpose, and devised an apparatus which operates efficiently and remains

in use despite possible damage to or disability in one or more of the hold-down units.

In carrying out the invention, specific reference to the drawings indicates a typical squaring shear at 10, its ram at 11, its bed at 12, and its sides at 10a. As shears of this type are standard, the connections for the operation of the ram have merely been shown in part and need not be described. For the purpose of the hold-down mechanism, a power shaft 13 running crosswise 10 of the machine is employed, the same having a series of substantially semi-circular cams 13a at points suitably spaced to induce the operation of a set of hold-down plungers 14.

Each plunger 14 is mounted in an independent 15 unit represented by a block 15 of substantially square form, the series of blocks being bolted as indicated at 16 between a pair of frame plates 17 carried by the sides 10a of the machine.

Each cam 13a is adapted to bear upon a roller 18 carried by a cross lever 19 whose rear end is pivotally supported at 19a by a hanger 20. The frontal portion of each lever 19 pivotally receives at 19b a depending pin 21 which has a thread at its upper portion to receive a nut 22 with a nut lock 23 above it and a free washer 24 below it. The balance of the pin below the washer 24 is taken up by an expansive spring 25. The latter is adapted to bear upon a long bar 26 extending freely between the two frame plates 17. The bar 26 rests on the head portions 27a of a series 30 of primary plungers 27.

Each plunger 27 is fitted with a leather or other packing 28 at its lower end, as clearly shown in Fig. 3, to make a snug fit in a vertical circular bore 15a in the upper portion of the block 15. The lower end of the bore 15a opens on a circular bore 15b of larger diameter, which continues to the bottom of the block, receiving a closure in the form of a plate 29 secured to the block by 35 screws 30.

Within the bore 15b is located the hold-down plunger 14, whose head 14a is fitted with a suitable packing 14b to snugly fit the wall of the bore. Between the head of the plunger and the 45 plate 29 is disposed an expansive spring 31.

The top of the block 15 is sunken at 15c to provide an annular well, the inner wall of the latter being an upward extension 15d of the stock of the block 15 which forms the wall of the bore 15a. A cross duct 15e extends from the bottom of the well 15c into communication with the bore 15a; also, a similar passage 15f extends outwardly to a tube 32 which rises along side the extension 15d to a high point in the well 15c.

In the operation of the hold-down mechanism its normal positions may be considered as indicated in Figs. 2 and 3. It is seen in Fig. 2 that the flat portion of each cam 13a is now above the related lever 19. The latter is thus at the upper end of its operation and is preferably maintained there by a spring 33 between its front end and the top of the machine 10. However, when the shaft 13 is given a partial turn, the prominent portions of the cam profiles will bear down on the rollers 18 of the levers 19, causing these to press down on the bar 26 through the agency of the pins 21 and the intermediate springs 24. The bar 26 in turn presses down the set of primary plungers 27 which transmit energy through the hydraulic medium in the block bore 15a to the related hold-down plungers 14. Owing to the greater area of the plunger heads 14a the action of the primary plungers 27 will impart a correspondingly greater pressure to the plungers 14, procuring a powerful hold-down action on the work. As the stroke of the plunger 14 is limited by the thickness of the work, it is the province of the top springs 25 to take up excess motion in the pins 21; and the springs 31 are, of course, provided to retract the hold-down plungers 14 the moment the pressure from above has been released, such as by a further or reverse partial turn of the mainshaft 13 to restore the cams 13a to the normal position shown, in which event the springs 25 and 33 procure the lifting of the lever 19.

It is seen from the above description that the master control of the hold-down mechanism is mechanical and extends only to the bar 26. Beyond the latter the hydraulic units are in a series numbered or spaced as the need may dictate and independent from one another as to action or effect. Thus, inefficiency or failure in any of the units will not be transmitted to the other units; and the removal of any defective units for attention or repair leaves the other units fully able to continue their work, so that the machine need not be out of service at any time.

The object of the well 15c in the top of each block 15 is to assure the maintenance of the proper amount of hydraulic liquid in the plunger bore 15a. Thus, what liquid may work past the plunger packing 28 will accumulate above the same and eventually flow over the exterior 15d into the well 15c. The latter already has a spare supply of the liquid, as indicated in Figs. 3 and 4, which replenishes the supply in the bore 15 by way of the passage 15e. In this connection, the tube 32 serves as an air vent and relieves such pressure as may resist the entry of the replenishing fluid.

It will be evident that I have provided a hold-down mechanism which is not a general hydraulic system with pipes, master cylinders, valves and other complications. The machine is ostensibly of simple mechanical design; yet it employs the powerful and advantageous hydraulic factor, but only in the zone of application and in the simple and desirable unitary form, whose advantages have been related. A machine so constructed is for the above reasons not only less costly than a fully hydraulic one, but is far more efficient and economical to maintain, since it need not be laid up or dismantled

in case of disability or failure in one or more of the hold-down elements. Also, the novel mechanism is designed for operation without attention or repair to its hydraulic units, since the liquid in these is a lubricant and is automatically maintained at working capacity.

I claim:

1. A hold-down mechanism for shears comprising a series of identical units, each unit being in the nature of a block perforated with longitudinally communicating bores of different diameters, a plunger in the smaller bore, a second plunger in the larger bore and forming a hold-down element by hydraulic action when a liquid is interposed between the plungers, a single bar extending longitudinally over the external ends of all of the smaller plungers, and means to actuate the bar with the effect of advancing all of such smaller plungers simultaneously.

2. The structure of claim 1, and a pair of stationary side bars receiving the series of units between them, said longitudinally extending bar being disposed between said side bars and guided thereby.

3. The structure of claim 1, said bores being vertical, and means in the region of the upper bore to replenish such of the liquid as may escape from the action of the plunger therein.

4. The structure of claim 1, said bores being vertical, and means in the region of the upper bore to replenish such of the liquid as may escape from the action of the plunger therein, such means comprising an upward extension of the wall of the upper bore and defining an annular well above the extension, and the extension being transversely perforated to establish communication between the lower portion of the well and said upper bore.

5. The structure of claim 1, said bores being vertical, and means in the region of the upper bore to replenish such of the liquid as may escape from the action of the plunger therein, such means comprising an upward extension of the wall of the upper bore and defining an annular well above the extension, the extension being formed with transverse perforations between the lower portion of the well and said upper bore, and a vent tube directed from one of the perforations upwardly to terminate above the extension.

6. A hold down mechanism for shears comprising a series of work clamping elements, a separate and self contained hydraulic operating unit for each element, each unit comprising a large cylinder and a small cylinder communicating therewith, plungers in said cylinders, means engageable with and operable to actuate simultaneously all of said plungers in said small cylinders to transmit power to said larger plungers to actuate the same, and said larger plungers being formed to comprise clamping elements.

7. A hold down mechanism for shears comprising a series of work clamping elements, a separate and self contained hydraulic operating unit for each element, a primary control plunger for each unit, a secondary plunger for each unit operable by said primary plunger and formed to provide a work clamping portion, and a pressure bar engageable with all of said primary plungers to actuate them simultaneously.

ROBERT LESLIE BROWNLEE.
